Atty's

UNITED STATES PATENT OFFICE.

ISAAC A. BAUM, OF CHICAGO, ILLINOIS.

WOOD AND METAL DOOR FRAME.

Application filed December 27, 1927. Serial No. 242,633.

My invention relates to buildings and particularly to a novel means for framing a wall opening.

In some types of construction, the architect prefers to utilize wood trim for the door and window openings. In order to facilitate such construction, and at the same time to provide a rigid steel element corresponding to the usual rough buck, I have designed the improvement illustrated herein, in which the desired results are accomplished in a satisfactory manner. The metal frame corresponding to the rough bucks may be first installed, and the tile or masonry walls incorporated therewith, suitable anchors being provided for permanently joining the two. Preferably, also, the metal element is projected outside of the limits of the masonry and the margins are rebent to provide a plaster terminal and a ground. Suitable means are also provided for rigidly joining a wood jamb and wood moulding to the metal frame.

My invention will be more readily understood by reference to the accompanying drawing, in which—

Fig. 1 is a transverse sectional view through a portion of a wall and door opening to which my improvement has been applied.

Fig. 2 is a face view of the metal element with the wood trim removed, and

Fig. 3 is a view similar to Fig. 1 showing a slightly modified form of the invention.

In the drawings I have indicated a wall composed of tile, to which lath 11, and plaster 12 is applied. The frame element corresponding to the rough bucks, consists of a flat plate, 13, of metal of substantial thickness and rigidity, having inwardly and backwardly bent margin 14, which constitute terminals for the plaster, the extremities serving as a plaster ground. Welded to the inner face of the plate 13 are continuous angular members, one leg 15 of which acts to position the plate relative to the tile, and another leg 16 of which serves as a means of attachment for an anchor 17.

On the front face, I mount by welding or otherwise, a pair of oppositely disposed clips 18, the free ends 19 of which are offset laterally, to provide an undercut space for engagement by the jamb holding clips. One

leg 20 of the clip underlies the portion 19, while the other leg 21 is adapted to lie alongside of the jamb 22, and to be secured thereto by nails. Wedges indicated at 23 are employed for positioning the jamb relative to the metal buck. After the jamb has been positioned by means of wedges, the clips are applied and nailed as shown. This insures rigidity in one direction. In order to insure rigidity against lateral movement in either direction, I provide a pair of members 24, secured by welding or otherwise to the plate 13 and provided with oppositely disposed, inclined or diagonal surfaces 25. By projecting nails 26 or screws 70 through the jamb into contact with the inclined surfaces, the jamb is rigidly positioned against lateral movement. The nails or screws are inserted before the moulding 27 is applied, and the workman can readily see the location of the inclined members through the side opening between the jamb and the buck.

In the construction shown in Fig. 3, many of the parts remain the same, and the same reference characters are applied thereto where the parts are identical. However, the metal frame element or buck is somewhat different. It comprises a plate 28, the flat portion of which extends the full width of the wall including the plaster, and is then rebent as at 29 forming the diagonal portion, the marginal flanges 30 constituting the means for spacing the tile. A plaster terminal and ground are provided and the element has the advantage of increased stiffness and rigidity due to its channel shape. An anchor 31 in the form of a T is employed for securing the frame element to the tile, the ends of the T head underlying 90 the reentrant flange 29.

Obviously the construction is capable of other modifications and I do not wish to be limited except as indicated in the appended claims.

I claim:

1. In means for framing wall openings, the combination with the wall of a metal plate having a substantially flat portion extending the full width of the wall and plaster, and providing means at its margins for a plaster terminal and ground, a wood frame member, clips joining the wood to the metal elements, and moulding overlying said attaching means.

2. A flat member for wall openings comprising a flat sheet of metal, extending substantially the entire width of the wall and plaster, and provided with a plaster terminal at its margin, means on the inner face of the sheet for positioning the plate and anchoring it relative to a masonry wall, and means on the outer face of the sheet for holding and positioning a wood frame member relative thereto.

3. In means for framing a wall opening, the combination of a metal element extending substantially the entire width of the wall and plaster and having a plaster terminal at the margin thereof, means on the inner face of the metal member for anchoring the same relative to a wall, a wood jamb located outside of said metal member, metal clips engaging said metal member and said 20 jamb, and positioning members having an

inclined face adapted to co-operate with said jamb for positioning the same relative to movement in another direction.

4. In framing means for wall openings, a combination of a metal plate of substantial thickness extending substantially the full width of the wall and plaster, and having a rebent margin acting as a plaster terminal, means on the inner face of the plate for anchoring the plate relative to a masonry 25 wall, a wood jamb and wood moulding applied to the outer face of said plate and metal clips and positioning devices applied to the outer face of said plate and adapted to the outer face of said plate and adapted for co-operation with said jamb for holding 30 35 the same.

In testimony whereof I have affixed my signature.

ISAAC A. BAUM.
